US00D923400S

(12) **United States Design Patent** (10) **Patent No.:** **US D923,400 S**
Wang (45) **Date of Patent:** **** Jun. 29, 2021**

(54) **LID FOR WATER BOTTLE**

(71) Applicant: **SHENZHEN CAMPER ENTERPRISE CO., LTD.**, Shenzhen (CN)

(72) Inventor: **Longhong Wang**, Shenzhen (CN)

(**) Term: **15 Years**

(21) Appl. No.: **29/718,986**

(22) Filed: **Dec. 31, 2019**

(30) **Foreign Application Priority Data**

Oct. 15, 2019 (CN) 201930560960.7

(51) LOC (13) Cl. **07-99**

Primary Examiner — Catherine S Posthauer

(57) **CLAIM**

The ornamental design for a lid for water bottle, as shown and described.

DESCRIPTION

FIG. 1 is a front perspective view of a lid for water bottle, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the figures illustrate portions of the lid for water bottle that form no part of the claimed design.

1 Claim, 8 Drawing Sheets
